MOWER BAR SHOE INSERT

Donald F. Bishop, R.R. 3, Knoxville, Iowa

Filed Aug. 27, 1959, Ser. No. 57,345

Term of patent 14 years

(Cl. D40—1)

Fig.1

Fig.2

Fig.3

Fig.4

Fig.5

Fig.6

Fig.7

Fig. 1 is a top perspective view taken from the front and right side of a mower bar shoe insert showing my new design;

Fig. 2 is a left side elevational view thereof;

Fig. 3 is a front elevational view thereof;

Fig. 4 is a right side elevational view thereof;

Fig. 5 is a rear elevational view thereof;

Fig. 6 is a top plan view thereof; and

Fig. 7 is a bottom plan view of the same.

I claim:

The ornamental design for a mower bar shoe insert, as shown.
